(74) *Attorney, Agent, or Firm* — Thomas E. Lees, LLC

(57) **CLAIM**

The ornamental design for a personal microphone mount, as shown and described.

DESCRIPTION

FIG. 1 is a perspective view of a personal microphone mount;

FIG. 2 is a front elevational view of the personal microphone mount of FIG. 1;

FIG. 3 is a rear elevational view of the personal microphone mount of FIG. 1;

FIG. 4 is a left side elevational view of the personal microphone mount of FIG. 1;

FIG. 5 is a right side elevational view of the personal microphone mount of FIG. 1;

FIG. 6 is a top plan view of the personal microphone mount of FIG. 1;

FIG. 7 is a bottom plan view of the personal microphone mount of FIG. 1; and,

FIG. 8 is a perspective view showing the personal microphone mount in use holding a microphone.

The broken line showings of the FIGURES are for illustrative purposes only and form no part of the claimed design.

1 Claim, 4 Drawing Sheets
